UNITED STATES PATENT OFFICE.

CHARLES A. STUART, OF KENOSHA, WISCONSIN, ASSIGNOR TO SIMMONS COMPANY, OF KENOSHA, WISCONSIN, A CORPORATION OF DELAWARE.

DESIGN FOR A BEDSTEAD FRAME.

Application filed August 24, 1922. Serial No. 3,550. Term of patent 3½ years.

To all whom it may concern:

Be it known that I, CHARLES A. STUART, a citizen of the United States, and a resident of the city of Kenosha, county of Kenosha, and State of Wisconsin, have invented a new, original, and ornamental Design for a Bedstead Frame, of which the following is a specification, reference being had to the accompanying drawing, forming part thereof.

The figure is a perspective view of a bedstead frame showing my new design.

I claim:

The ornamental design for a bedstead frame as shown.

CHARLES A. STUART.
